CLAIM

The ornamental design for a faucet body, as shown and described.

DESCRIPTION

In a preferred embodiment, the nature of this product is a body for a faucet.

FIG. 1 is a right, top, front perspective view of a faucet body according to my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a left, top, front perspective view of a spout body according to another embodiment of my new design, the various views thereof being mirror images of the views shown in FIGS. 2-7;

FIG. 9 is a right, top, front perspective view of a faucet body according to another embodiment of my new design;

FIG. 10 is a front elevational view thereof;

FIG. 11 is a rear elevational view thereof;

FIG. 12 is a right side elevational view thereof;

FIG. 13 is a left side elevational view thereof;

FIG. 14 is a top plan view thereof;

FIG. 15 is a bottom plan view thereof; and,

FIG. 16 is a left, top, front perspective view of a spout body according to another embodiment of my new design, the various views thereof being mirror images of the views shown in FIGS. 10-15.

The broken line representations in the figures, including broken line representations of spray head and handle environment, are for the purpose of illustration only, and form no part of the claimed design.
